UNITED STATES PATENT OFFICE.

WILLIAM BENDER, OF CHICAGO, ILLINOIS, ASSIGNOR TO AJAX FORGE COMPANY, OF CHICAGO, ILLINOIS, A CORPORATION OF DELAWARE.

SWITCH-STAND.

1,273,134.

Specification of Letters Patent.

Patented July 23, 1918.

Application filed May 17, 1915. Serial No. 28,680.

To all whom it may concern:

Be it known that I, WILLIAM BENDER, a citizen of the United States, residing at Chicago, in the county of Cook and State of Illinois, have invented certain new and useful Improvements in Switch-Stands, of which the following is a specification.

This invention relates to a switch stand adapted for use in operating the switch point rails of a railway switch.

It is desirable that the point rails of a railway switch be maintained in close contact with the corresponding fixed rails of the railway track, in order to prevent derailments or other accidents which may follow from an improper adjustment of the point rails, and it is therefore the purpose of this invention to provide an improved switch stand, or switch-throwing apparatus which may be conveniently operated for throwing the point rails and effectively maintaining a proper relative adjustment of the desired point rail with respect to the adjacent fixed rail.

The principal object of the invention is to provide a switch stand comprising parts which are relatively adjustable, in order that the throw of the switch point rails with respect to the fixed rails may be varied to maintain at all times the proper relative adjustment of the point rails and fixed rails, even after wear has taken place on the rails and in the parts of the switch-throwing apparatus. A further object is to provide a switch stand which may be manipulated to vary the adjustment of either point rail with respect to the adjacent fixed rail independently of the corresponding adjustment of the other point rail with respect to the other fixed rail. Another object is to provide a device of the kind referred to in which the adjustment may be conveniently and quickly made by the usual switch operator. Still another object is to provide an improved connection between the operating lever and shaft of the switch stand, whereby the limits of rotation of the shaft and the corresponding limits of throw of the switch rod may be varied without varying the limits of throw of the lever.

These and other objects of the invention will appear more clearly in the following specification, taken in connection with the accompanying drawings, in which one embodiment of the invention is illustrated.

In the drawings—

Figure 1 is a top plan view of a railway switch showing my improved switch-throwing apparatus connected to the point rails of the switch.

Fig. 2 is a sectional view taken on the line 2—2 of Fig. 1, showing the switch stand in elevation.

Fig. 3 is a side elevation of the switch stand, looking toward the left in Fig. 2.

Fig. 4 is a perspective view of the adjustment member carried by the shaft upon which the operating lever is mounted.

Fig. 5 is a perspective view of one end of the operating lever.

Fig. 6 is a top plan view of the switch stand, showing a portion of the frame or housing broken away.

Fig. 7 is a sectional view, taken on the line 7—7 of Fig. 6.

Fig. 8 is a perspective view of the switch-throwing crank and shaft, and the gear through which said elements are actuated.

Fig. 9 is a sectional view, taken on the line 9—9 of Fig. 7; and

Fig. 10 is a sectional view, taken on the line 10—10 of Fig. 7.

In the drawings, the fixed or continuous rails 15 and 16 of the railway track are shown as mounted upon the usual railway ties 17, and supported upon these ties adjacent the fixed rails are the movable switch point rails 18 and 19, which are adapted when in proper positions to co-act with the fixed rails 15 and 16, respectively. The switch point rails are arranged to slide upon the plates 20, which are secured to the railway ties, and the point rails are connected to move in unison by means of a switch rod 21. This switch rod is connected to the point rails adjacent their extremities by means of intermediate connecting means 22, and the switch rod extends beneath the fixed rails of the track for connection with suitable switch-throwing apparatus, such as my improved switch stand, which I have designated generally by the numeral 23.

My improved switch stand comprises a frame or housing 25, having oppositely extending base flanges 26 which are adapted to seat upon two adjacent railway ties 27, to which they are secured by means of spikes or studs passing through the apertures 28. It will be seen that the ties 27 are of greater length than the usual ties 17, so that they

extend outwardly beyond the extremities of the latter ties to provide a support for the switch stand at a suitable distance from the adjacent fixed rail. The frame 25 comprises a centrally located housing adapted to contain certain movable parts of the switch-throwing mechanism, and this housing comprises a removable cover portion 25^a having oppositely extending apertured flanges 29, which are rigidly secured to the adjacent parts of the base portion of the frame by means of studs or bolts 30.

The frame 25 is provided with a vertically extending hub or sleeve 31, in which is journaled the switch-throwing shaft 32. This shaft comprises a squared portion 33, which extends downwardly beyond the hub or sleeve 31 to engage an aperture of similar form in the hub 34^a of the switch-throwing crank 34. A bolt 35 extends through alining apertures in the hub and the portion 33 of the shaft, to secure said parts against relative displacement. The switch-throwing crank comprises two oppositely disposed crank arms 36, each having an integrally formed pin 37 projecting vertically therefrom adjacent its extremity. One of the pins is adapted to engage a circular aperture in one extremity of a connecting rod 38, which is pivotally connected at 39 to the switch rod 21 previously described. It will be seen that the rotation of the shaft 32 will operate through the crank arm and connecting rod to reciprocate the switch rod, and thus move the switch point rails with respect to the fixed rails. The switch-throwing crank 34 is provided with two crank arms 36, so that after one of the arms becomes worn or imperfect with use the crank 34 may be reversed in its position on the shaft 32, and the connecting rod 38 connected to the pin of the other crank arm.

The shaft 32 is also provided with an upwardly extending portion 40 of rectangular cross section, which is adapted to engage a similar aperture formed in the hub of a bevel gear sector 41. The portion 40 of the shaft and the hub of the bevel gear are provided with alining apertures adapted to be engaged by a pin or rivet 42, and the hub of the bevel gear is provided with an outwardly extending cylindrical part which is journaled in the sleeve 36 formed integrally with the cover portion 25^a of the housing. It will be seen that the hub of the bevel gear seats upon the upper extremity of the sleeve or hub 31 of the frame 25, thus supporting the shaft 32 and parts carried thereby against vertical displacement downwardly. The hub of the switch-throwing crank 34 similarly engages the lower extremity of the sleeve 31, thus preventing vertical displacement upwardly of the shaft 32.

The bevel gear sector 41 meshes with a

bevel pinion 45, which is fixed by a pin 46, or other suitable means, upon the inner end of a horizontal operating shaft 47 within the centrally located housing of the frame 25. The shaft 47 is journaled in a suitable bearing formed in the outwardly extending projections 48 and 49 of the base and cover portions, respectively, of the frame. These projections are provided with outwardly extending lugs 50 having alining apertures therein which are engaged by studs or bolts 51, whereby the parts are mutually secured. It will be seen that the rotation of the horizontal shaft in its bearing will operate, through the bevel pinion 45 and the bevel gear sector 41, to rotate the shaft 32, and thereby reciprocate the switch rod.

The outwardly projecting portion of the shaft 47 has mounted thereon an adjustment member 55. This adjustment member is provided with a horizontally-extending bore 56, which closely engages the shaft, and with radially extending apertures 57 adapted to register with corresponding apertures in the shaft. These alining apertures are engaged by pins 58, whereby the adjustment member is secured in fixed position on the shaft. The adjustment member is further provided, midway between its opposite vertical faces, with a socket 59 which intersects the bore of the adjustment member and provides a suitable chamber around the shaft within the adjustment member. An operating lever 60 is adapted to enter the socket 59, and to fit closely the vertical walls thereof, being provided at its extremity with a circular aperture 61, which is adapted to receive the portion of the shaft which extends through the socket. In this manner the operating lever is pivotally mounted on the shaft, but is prevented from horizontal displacement thereon by the walls of the socket.

The angular movement of the operating lever 60 with respect to the shaft 47 and the adjustment member 55 is limited by two oppositely disposed lugs or flanges 62, which are formed integrally with the adjustment member, and which extend on opposite sides of the operating lever in the path of movement thereof with respect to the shaft 47. The relatively adjacent faces 63 of the lugs or flanges are inclined outwardly and away from the axis of the bore 56, and spaced apart so as to permit a desired maximum degree of pivotal movement of the lever on the shaft before said lever engages one of the faces. Each of the lugs or flanges 62 is provided with a threaded aperture 64 lying in the same radial plane as the socket 59. Each of these threaded apertures is engaged by a stud or set screw 65, which may be caused to extend beyond the face 63 of the corresponding lug 62

for the purpose of limiting the pivotal movement of the lever with respect to the shaft. Each of the threaded apertures 64 terminates at the outer side of the corresponding lug 62 in a socket 66 adapted to receive a portion of the head of the corresponding stud 65. The walls of the socket 66 are provided with alining slots or notches 67, which lie in planes parallel to the axis of the bore, and which are adapted to be engaged by pins 68 extending through the apertures in the heads of the studs 65. It will be apparent that after one of these studs has been adjusted to the desired position, the pin may be passed through the aperture in the head and through the adjacent alining slots 67 to prevent rotation of the stud from its adjusted position. The usual cotter pins are preferably used for this purpose.

The lever 60 is provided at its outer extremity with an integrally formed heavy weight 70 adapted to maintain the parts of the switch-throwing mechanism in their proper position after they have been adjusted by the operator. The extremity of the weight has formed therein a notch or groove 71, which extends parallel to the axis of the shaft and which provides suitable flanges on opposite sides of the notch to be engaged by the hand of the operator for throwing the lever. A U-shaped bracket 72 is secured by spikes 73 on the ties 27 at each side of the shaft, and in the same vertical plane in which the lever moves. One of the brackets 72 is adapted to coact with the lever in either position thereof to support the same against further downward movement. The projecting part of the lever carrying the heavy weight 70 serves to maintain the lever against displacement from the supporting bracket.

When the lever is in the position shown in the drawings, viz., resting on the bracket 72 at the left of the shaft 47, as viewed in Figs. 1 and 3, the parts of the switch mechanism will be in such position that the point rail 18 is thrown into contact with the fixed rail 15, while the point rail 19 is thrown or displaced from the fixed rail 16. When the switch lever is thrown into the reverse position, resting on the bracket 72 at the right of the shaft 47 as viewed in Fig. 3, for instance, the switch-throwing lever 55 will have been operated to move the point rail 19 into contact with the fixed rail 16 and to displace the point rail 18 from the fixed rail 15. The lever 60 thus moves through a fixed arc during the process of changing the switch point rails from one adjusted position to the other.

As my improved switch-throwing mechanism is illustrated in the drawings, it will be apparent that when the operating lever 65 is thrown to the left, as viewed in Fig. 3,

for instance, the point rail 18 will coact with the fixed rail 15, and when the operating lever is thrown to the right, as viewed in Fig. 3, the point rail 19 will coact with the fixed rail 16, while the point rail 18 will be displaced from the fixed rail 15. When the rails and switch-throwing mechanism are first assembled and adjusted, they may be so arranged that successive operations of the lever will result in the proper corresponding adjustment of the point rails with respect to the fixed rails.

It will be apparent, however, that after the fixed rails and switch point rails have become worn with continued use the switch point rails may no longer contact the adjacent fixed rails in a manner to guide properly the wheels of the rolling stock when they pass the point of the switch, which may result, for example, in the wheels of successive cars, or successive wheels of the same car, passing on opposite sides of a point rail, which action will result in a derailment, or other serious accident. My invention is designed to overcome this difficulty, since when it is found that the rails have become worn, so that the point rails no longer make proper contact with the adjacent fixed rails, the studs 65 may be adjusted to provide a greater throw of the switch rod 21 in the desired direction until the space between the point and fixed rails has been taken up and the difficulty overcome. For instance, assuming that the point rail 18 does not properly contact with the fixed rail 16, as viewed in Figs. 1 and 2, the operator may withdraw the pin 68 from the lower one of the studs 65, as viewed in Fig. 3, for instance, and rotate the stud inwardly so that its inner extremity projects to a greater extent beyond the face 63 of the corresponding lug 62, thereby rotating the adjustment member 55 downwardly and to the left with respect to the lever 60. This will result in moving the switch rod 21 and point rail 18 to the left, as viewed in Fig. 2, while the lever remains stationary. In this way the point rail 18 may be adjusted until it properly contacts with the fixed rail 15.

When it is desired to throw the switch into the reverse position, the lever is thrown to the right, as viewed in Fig. 3, as previously described. During the first part of this movement it will be evident that the lever will rotate without causing a rotation of the adjustment member and the operating shaft, but when the lever engages the extremity of the uppermost stud 65, as viewed in Fig. 3, the shaft will begin to rotate, and will continue to be rotated until the operating lever has been carried over into the reverse position. If when the lever is in reverse position, it be found that the point rail 19 does not properly contact with the fixed

rail 16, the stud 65, at the right of the lever as viewed in Fig. 3, may be adjusted in the member 55 until the limit of rotation of the shaft is such as to produce the proper adjustment of the point rail 19 with a fixed throw of the lever. The adjustment member 55, comprising the adjustable stud 65, is preferably so adjusted that each of the point rails will coact with the adjacent fixed rail before the lever has reached the supporting bracket 72 in the corresponding position of said lever. In this way a strain is put on the parts of the mechanism after the point rail has contacted with the fixed rail, so that all the backlash or play in the moving parts of the mechanism may be taken up before the lever reaches the adjacent supporting bracket. Then when the lever is supported on the bracket, the heavy weight 70 will serve to maintain a very tight and effective adjustment of the switch rails and the switch-throwing mechanism. It will also be apparent from the foregoing description that by means of the stud 65 and the adjustment member 55, the limit of the throw of either point rail of the railway switch toward the adjacent fixed rail may be adjusted independently of the corresponding limit of the throw of the other point rail toward the other fixed rail; that is, the throw of one point rail from open position toward the fixed rail with which it is adapted to coact, and the pressure of contact therewith, may be regulated in degree independently of the throw of the other point rail toward and its contacting pressure with the other fixed rail. In this way both of the point rails may be caused to assume the proper relative positions with respect to, and to bear with the desired pressure on, the fixed rails by the very simple operation of adjusting the studs 65 in the adjustment member as wear occurs and the adjustment becomes necessary. It will be understood that the operating lever moves through a fixed arc or path and that the limits of movement of the switch rod in opposite directions, and the corresponding limits of rotative movement of the shaft 47, are varied by adjusting the studs 65 so as to vary the amount and occurrence of the lost motion of the lever 60. A further advantage of my switch stand is that it is very simple and rigid in construction, as well as efficient in operation. It is so arranged that the operating lever 60 moves in a vertical plane parallel to the rails of the railway track; and this enables the device to be accommodated by a relatively limited space adjacent the railway track, so that it may be used in those locations in which there is a relatively limited space between the track and another adjacent track or other object.

65 While I have shown and described a par-

ticular embodiment of my invention, and have described a particular manner of operation for purposes of illustration, it will be understood that my improved switch stand may be embodied in various other structures of widely divergent form without departing from the scope of the invention as defined by the appended claims.

I claim:

1. In a device of the class described, an operating shaft, an adjustment member fixed on said shaft, an operating lever pivotally mounted on said shaft, said adjustment member having integral parts extending on opposite sides of said lever, and adjustable means carried by said integral parts and lying in the path of movement of said lever to limit the pivotal movement thereof with respect to said shaft. 75
2. In a device of the class described, an operating shaft, an adjustment member fixed on said shaft, an operating lever pivotally mounted on said shaft, said adjustment member having parts extending on opposite sides of said lever to limit the pivotal movement of said lever with respect to said shaft, and studs extending through said parts of the adjustment member and adapted to engage said lever for varying the rotation of said shaft with a given rotation 80 of said lever. 85
3. In a device of the class described, a shaft, an adjustment member fixed on said shaft, an operating lever, said adjustment member having an inwardly extending 100 socket through which said shaft extends, said lever being pivoted on the shaft in said socket, and studs extending through the opposite walls of the socket in the plane of movement of said lever. 105
4. In a device of the class described, a shaft, an adjustment member fixed on said shaft, an operating lever, said adjustment member having an inwardly extending 110 socket through which said shaft extends, said lever being pivoted on the shaft in said socket, said adjustment member having integrally formed flanges extending on opposite sides of said lever, and adjustable studs 115 extending through said flanges and adapted to engage said lever. 115
5. In a device of the class described, a shaft, an adjustment member fixed on said shaft, an operating lever, said adjustment member having an inwardly extending 120 socket through which said shaft extends, said lever being pivoted on said shaft in said socket, said adjustment member having integrally formed flanges extending on opposite sides of said lever, adjustable studs extending through said flanges and adapted to engage said lever, and means to secure said studs in adjusted position. 125
6. In a device of the class described, an operating shaft, an adjustment member 130

fixed on said shaft, an operating lever pivotally mounted on said shaft, and adjustable members threadedly engaging said adjustment member and arranged in the path of movement of said lever to vary the rotation of said shaft with a given rotation of said lever.

7. In a device of the class described, an operating shaft, an adjustment member mounted on said shaft, said adjustment member being provided with a socket, an operating lever pivotally mounted in said

socket, and adjustable means threadedly engaging the walls of said socket and arranged in the path of movement of said lever to 15 vary the rotation of said shaft with a given rotation of said lever.

In testimony whereof, I have subscribed my name.

WILLIAM BENDER.
